UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

LOCKING-HANDLE COCK.

Application filed October 15, 1919. Serial No. 330,787.

To all whom it may concern:

Be it known that I, CLYDE C. FARMER, a citizen of the United States, residing at Pittsburgh, in the county of Allegheny and State of Pennsylvania, have invented new and useful Improvements in Locking-Handle Cocks, of which the following is a specification.

This invention relates to cocks, and more particularly to an angle cock as employed on railway cars for controlling communication through the brake pipe or other fluid pressure train pipe.

It has sometimes happened that an angle cock in the train brake pipe has been closed by an unauthorized person or has been negligently closed, so that the engineer loses control of the brakes of the train, especially if an angle cock be closed near the head end 20 of the train.

Serious accidents are then very liable to happen, as the engineer cannot apply the brakes to stop the train in case of necessity.

The principal object of my invention is to obviate the above difficulty by providing a cock which can be locked in the open and closed positions of the cock.

In the accompanying drawing; Fig. 1 is an elevation of an angle cock device embodying my invention; Fig. 2 a section of the locking handle portion of the cock on the line 2—2 of Fig. 3; Fig. 3 a section on the line 3—3 of Fig. 2; Fig. 4 a section similar to Fig. 2, showing the handle in its raised position; and Fig. 5 an end view of the locking member.

As shown in the drawing, the angle cock device may comprise the usual cock body 1 and a locking handle 2 constructed similarly to the locking handle disclosed in the prior Reissue Patent No. 12,574 of Inches & Hosker, dated Dec. 11, 1906.

The handle 2 is pivoted to a member 3 which is secured to the cock key and is provided with a lug 4 adapted to engage stops 5 and 6 in the cock body 1 when the key is turned to its respective open and closed positions.

The handle is also provided with lugs 7 and 8, the lug 7 being adapted to engage the stop 6 when the handle is in its open position, and the lug 8 the stop 5, when the handle is in its closed position.

According to my invention, a locking mem-

ber 9 is provided for preventing movement of the handle 2. The key member 3 is provided with an upwardly extending lug 10, having a concavity 11 on its edge and the member 9 is provided with a cylindrical section 12 adapted to engage in the concavity 11 for locking the parts against movement, the opposite side of the section being cut away to provide a flat face 13.

The locking member 9 is mounted in an enclosing casing 14, forming part of the handle 2 and at one end is provided with a cavity 15 for receiving a key 19. An escutcheon 16 is secured in the casing 14 adjacent to the end of the locking member 9.

An eccentric weight 17 is secured to the member 9 and is so positioned as to tend to maintain the locking member in its locked position.

In order to turn the handle 2, it is necessary to first lift the same, so as to disengage the lug 7 or 8, as the case may be, from the stop 5 or 6.

With the locking member 9 in the position shown in Fig. 2, the section 12 engages within the concavity 11 and thus prevents the handle 2 from being lifted, so that the handle cannot be turned from either its open or its closed position.

If it is desired to operate the cock, a key 19, corresponding with the contour of the slot in the escutcheon, must be inserted and the member 9 turned, so that the flat face 13 is adjacent to the concavity 11.

Then the handle 2 may be lifted and turned to the desired position.

When the handle has been lifted, the flat face 13 will be adjacent to a face 18 on the lug 10, so that while in a lifted position, the member 9 cannot be rotated, nor can the key 19 be removed.

The handle 2 must therefore be moved to its full open or closed position and then allowed to drop to its locked position, before the member 9 can be rotated and then the key 19 must be turned so as to move the member 9 to its locked position, so that the key will align with the slot in the escutcheon and thus permit its removal.

The action of the weight 17 is such that the member 9 will be maintained in its locked position, regardless of jarring when the train is in motion.

The above described construction prevents

the movement of the angle cock handle except by a person provided with the proper key, and it is intended that the trainman in charge of the train shall keep possession of 5 the key and be held responsible for the same.

Having now described my invention, what I claim as new, and desire to secure by Letters Patent, is:—

1. The combination with a cock device 10 comprising a valve body having stops and a vertically movable handle having a projection for engaging one of the stops, of a member mounted on the handle for locking said handle against vertical movement from normal position and rotatable to a position for 15 releasing the handle and means for preventing rotation of said member from its release position in the raised position of the handle.

2. In a cock device, the combination with 20 a handle for operating the cock key and piv-

oted for vertical movement from a normal position, of a rotatable member carried by the handle and adapted to lock the handle against vertical movement, a key for rotating said member, and means for preventing 25 rotation of said member and the turning of the key when the handle is in its raised position.

3. In a cock device, the combination with a member secured to the cock key and a vertically movable handle pivoted to said member for operating the key, of a rotatable locking device carried by the handle for engaging said member to prevent vertical movement of said handle, said member having 35 means for preventing rotation of the locking device when the handle is moved vertically.

In testimony whereof I have hereunto set my hand.

CLYDE C. FARMER.
